Inventor:

Floyd Vogel,
by Parker Cook,
Atty.

UNITED STATES PATENT OFFICE.

FLOYD VOGEL, OF HACKETTSTOWN, NEW JERSEY.

CUTTER HEAD AND GAUGE.

1,420,068.

Specification of Letters Patent. Patented June 20, 1922.

Application filed November 23, 1920. Serial No. 426,074.

To all whom it may concern:

Be it known that FLOYD VOGEL, a citizen of the United States, residing at Hackettstown, in the county of Warren and State of 5 New Jersey, has invented certain new and useful Improvements in Cutter Heads and Gauges, of which the following is a specification.

My invention relates to a new and useful 10 improvement in cutter heads and gauges therefor, and especially to a cutter head and gauge used in the forming of tapers on the end of sand cores.

The present practice is to form a number 15 of blank sand cores in stock core machines, then cut these cores to the desired length and then taper the ends of the cores by filing them or holding the end against an emery wheel. Cutting the tapers in this way takes 20 considerable time and the tapers formed are not accurate.

An object of my invention is to provide a means that will simplify the above procedure and cut the tapers in an accurate 25 manner.

Still another object of my invention is to provide a cutter head having a centrally located detachable guiding sleeve on its front face, a small central opening in its rear face 30 and a plurality of cutters or knives, capable of adjustment, located radially of the head. Also to provide a gauge to be used with the cutter head, that has a central lug or pin on its front face, designed to fit within 35 the opening in the rear face of the cutter head, so that the knives may be adjusted whenever necessary, to take up the wear of the cutting edges.

Still another object of my invention is to 40 provide a cutter head for tapering the ends of the sand cores, and one that will taper the cores accurately as to the length and degree of the taper; to provide an accurately centering gauge so that the knives may be 45 quickly adjusted; either for the different size tapers, between certain limits, or to take up the wear of the cutting edges, so that the knives will be accurately positioned at all times.

Still another object of my invention is to 50 provide a cutter head and gauge that may be made up in various sizes, the cutter head being provided with a detachable sleeve, so that sleeves may be made up in various sizes, 55 that is, with relation to their internal diameter, so that different size sleeves may be

used on a cutter head thus not necessitating a cutter head for every size taper desired. Numbers of each will be made up so that a number of cutting heads may be used on 60 one machine, to thus multiply production, or just one may be used on nearly any form of revolving spindle machine.

Still another object of my invention is to provide a cutter head and gauge, wherein 65 the gauge may be quickly inserted in the cutter head and by simply moving three set screws the knives may be set to conform with the selected gauge.

With these and numerous other objects 70 in view as will be disclosed as the invention proceeds my invention consists in certain new and novel constructions and combination of parts as will be hereinafter more fully described and pointed out in the claims. 75

Referring now to the drawings showing a preferred form of the invention:

Fig. 1 is a central longitudinal section of the cutter with the gauge shown in place;

Fig. 2 is a transverse sectional view on 80 line 2—2 of Fig. 1;

Fig. 3 is an end view of the cutter head;

Fig. 4 is a side elevation with the gauge removed; and

Fig. 5 is a detail of the gauge. 85

Referring now to the several figures in detail, a cutter head 1, is shown, having the rearwardly extending boss 2, which is tapered and internally threaded as at 3, while in the rear face 4, of the head and centrally thereof is provided the small opening 5.

The cutter head is provided with the three radial cut-out portions 6, as clearly shown in Fig. 2, through which the waste is 95 designed to pass, while located radially of the cutter head and substantially $\frac{1}{16}$ " off center are three slots 7, for the reception of the knives 8.

By positioning these slots and knives as 100 mentioned an edge is at all times presented to the work and tends to keep the knives in proper condition. A set screw 9, is provided for each knife so that the knives may be adjusted according to the work to be done 105 or as the edges wear down the set screws may be loosened, the knives pushed inwardly and the screws again set to tightly hold the knives in their adjusted position.

These knives are tapered at their cutting 110 edge 10, and the different heads of course may be provided with different tapered

knives, so that any size taper may be cut on the core, as required.

Formed in the body of the cutter head is a central pocket or chamber 11, which also tapers from its forward end to its rear, into which extend the cutting edges 10 of the knives 8, and into which pocket the work extends.

In the front of the cutter head is the 10 slightly depressed rim portion to thereby provide or form the positioning lugs or faces 12 which are provided in turn with the internally threaded holes 13 for the reception of the fastening or retaining screws 14 which 15 are placed about the rim 15 of a detachable centering sleeve 16.

This sleeve 16 is for correctly centering a gauge 17 and the core on its insertion to the knives 8, and is of sufficient length to provide against any movement of the core from its correct alignment with the knives in the cutter head. A number of different size sleeves may be used with one cutter head, that is a sleeve of one inch (internal diameter of opening) $1\frac{1}{4}$, $1\frac{1}{2}$, $1\frac{3}{4}$ or the 1 and the eighths etc. up to two inches may be used with the one cutter head, while a number in the same proportionate size may be used with a larger cutter head.

30 Referring now to the gauge 17 to be used in conjunction with the cutter head, it will be seen that it consists of the body 18, the knurled handle 19, the forward tapered end 20, and the small central aligning lug 21 on its front face.

In Fig. 1 is shown the gauge inserted within the cutter head, the lug or pin 21 fitting within the small opening 5 heretofore referred to. If the cutting edges of the knives 40 have worn and do not contact or register exactly with the tapered surface of the gauge the set screws 9 will be loosened, the blades correctly positioned and the set screws again tightened, and of course the operation is the same if a different size taper is desired.

By providing the sleeve 16 on the face of the cutter head with the opening 5 in the rear face of the cutter head, the gauge with the lug 21 thereon fitting within the opening 50 5 will be accurately centered and from which the knives may be accurately and correctly positioned or adjusted.

The gauge will then be removed and the core passed through the sleeve 16 and be accurately guided to the knives 8 which will form the taper quickly and accurately. After constant usage and wear the knives 55 may be again gaged and adjusted if found necessary.

60 These gauges of course are made up in all standard sizes both as to length and degree of taper, as well as the cutter heads, sleeves of the cutter heads and knives, so that with

complete sets of these cutter heads and gauges, any size core taper may be made.

From the foregoing it will be seen that I have provided a cutter head and gauge that may be made up in any and all sizes, that will quickly and accurately taper the material worked upon, and wherein the knives 70 may be accurately adjusted, or as they wear they may be brought up to a standard.

As before mentioned, cutter heads can be used in multiples, in fact they are in use with as many as twelve on each machine, 75 or they can be applied singly to any form of machine having the ordinary revolving spindle.

It is to be understood that although I have mentioned these heads as especially adapted 80 for tapering cores, they may be used for cutting any articles calling for an accurate taper at its end.

Also many slight changes may be made 85 as to form or arrangement of parts without in any way departing from the spirit and scope of the present invention.

Having thus described my invention, what I claim as new and desire to secure by Letters Patent is:—

1. A cutter head comprising a body having a chamber, a knife mounted upon the body and extending into the chamber, the body being provided at the opposite sides of the chamber thereof with work centering means which are fixed with relation to the body and unalterably mounted with relation to each other, the parts being so arranged that the work centering means may receive finished and spaced portions of a piece of work 100 whereby an unfinished intermediate portion of the work may traverse the chamber and is centered therein and accurately positioned for final dressing by the knife.

2. In combination with a gauge having a tapered end portion and a centrally located forwardly extending lug, a cutter head comprising a body, a chamber in said body and passageways extending from the outer surface of the body to said chamber, knives in said head arranged radially thereof and extending within said chamber, said knives adjustable in said head and means for holding them in a set position, a sleeve secured to the face of the cutter head, and an extension on the rear of the cutter head adapted to be secured to a revolving member, the rear wall of the body provided with an opening therein and arranged centrally thereof and of the said chamber and adapted to receive the lug of the gauge so that the knives in said head may be accurately centered and adjusted to the tapered portion of said gauge.

In testimony whereof I affix my signature.

FLOYD VOGEL.
